UNITED STATES PATENT OFFICE

JOHN J. REINHOLD, OF MARIETTA, PENNSYLVANIA

ADVERTISING DEVICE FOR ORDERING DAIRY PRODUCTS

Application filed July 10, 1931. Serial No. 549,918.

The present invention relates generally to a device for ordering supplies, such as dairy products, and more specifically to an advertising novelty serving that purpose.

The ordering of milk, cream, or other products from a delivery man, who makes deliveries at an hour when the ordinary household is still asleep, has heretofore been attended with considerable trouble, inconvenience and uncertainty. Usually any change from the usual daily delivery quantity is made by writing the changed order upon a slip of paper and dropping it in an empty milk bottle. In some instances the slip is blown away before the milkman arrives, in other instances the writing on the slip may be obliterated by rain, and again it may be entirely overlooked by the delivery man, any one of which results in the order not being filled and inconvenience to the housewife.

Some of the objects of the present invention are to provide a simple and efficient device for giving an order; to provide an ordering device which serves also as an advertising medium and can be given away by the advertiser; to provide a device in the form of a cap which is designed to fit over and be supported upon the top of a milk bottle; to provide a cap having an attached insert adapted to be written upon and which permits the writing to be wiped off or erased after use so that the surface of the insert can be used repeatedly; to provide a novel combination of order cap and holder therefor; and to provide other improvements as will hereinafter appear.

In the accompanying drawing Fig. 1 represents a top plan of an order device embodying one form of the present invention; Fig. 2 represents a plan of the inside of the device; Fig. 3 represents a side elevation of the device as applied to a bottle; Fig. 4 represents a section on line 4-4 of Fig. 1; Fig. 5 represents an elevation of the device as mounted upon a novel holder therefor; and

Fig. 6 represents a side elevation of the holder with the device attached thereto. Referring to the drawing one form of the present invention consists of a cap 10 preferably of circular contour and of a size to fit snugly over the mouth of an ordinary milk bottle. Of course the size and contour of the cap will depend upon the article with which it is to be associated. The top face of the cover 10 serves to mount a label 11 containing preferably an advertisement since the device is in the nature of a novelty to be bought in quantity by an advertiser and distributed to the public.

In order to use the cap 10 for giving an order the inner face of the cap has an attached disc 12 made of a suitable material to receive lead, ink or other marks while allowing such marks to be wiped off or erased to restore the mark receiving surface to its original blank appearance. This surface has impressed therein or otherwise permanently displays a list of commodities with quantity receiving spaces 13 opposite thereto in order to receive a mark or marks indicating the quantity desired of that particular product. In the present instance the commodities are dairy products and the left side of the disc 12 shows a permanent list of milk grades, and cream, while substantially diametrically across the disc and two columns of the spaces 13 so arranged that two spaces are horizontally opposite each different grade of milk. One column is identified by the abbreviation for "quart" and the other column by the abbreviation for "pint". At the right of the disc 12 there is a space in which any message can be written and in this example it is used for notifying a discontinuance of service until a noted date.

Since the order cap 10 can be used repeatedly and is designed for long use it is permanently shaped. It is also extremely desirable to have it where it can be readily found and convenient for use. Also since it

is an advertising medium it should be mounted with its advertising message in full view at all times. To these ends therefore a mounting element has been devised consisting in the present instance of a plate 14 of circular contour having a projecting pin or hook 15 so disposed and located as to suspend the cap 10 upon the face of the plate 14 in concentric relation. A hole 16 is provided in the wall of the cap 10 at the proper place to cause the cap 10 to hang with its advertisement in correct reading position. Preferably the plate 14 has a central aperture 17 which is closed by the cap 10 when the latter is supported upon the hook 15. The plate 14 has a rearwardly extending rigid bracket 18 for attachment to a wall 20 or other support and the arrangement is such that the plate 14 is carried at an angle to more effectively display the cap 10.

When the device is not in use it is mounted upon the holder ring 14 where its angular position assures the advantageous display of the advertising matter.

When used it is removed from the holder ring 14 and the quantity of milk, cream and the grade of each is then indicated upon the blank column and the device then fitted on the top of a milk bottle. There it is seen by the delivery man who removes it and looks at the inside thereof for his order which is then filled and the cap placed upon a full bottle ready to be taken in for use again. The order is now wiped off of the disc 12 and the cap replaced upon its holder for use again.

It will now be apparent that an order device capable of carrying out the desired function has been devised which is simple in construction, easily used by anyone, and extremely effective as an advertising medium. While any form of advertisement can be used with it the more direct type is that dealing with commodities which call for the use of milk and cream.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. The combination with a milk bottle having a large open mouthed top, of a cap of permanent circular contour slightly larger than said mouth adapted to rest thereon with a depending flange to overhang said mouth to prevent accidental removal of the cap, and an order disc attached to the inner face of the cap whereby the same is protected during use.

2. The combination with a milk bottle having a large open mouthed top, of a cap of

permanent circular contour slightly larger than said mouth adapted to rest thereon with a depending flange to overhang said mouth to prevent accidental removal of the cap, and an order disc attached to the inner face of the cap whereby the same is protected during use, said disc being of material to permit order marks to be washed or wiped off.

Signed at Philadelphia, county of Philadelphia, State of Pennsylvania, this 8th day of July, 1931.

JOHN J. REINHOLD.
